UNITED STATES PATENT OFFICE.

JOSEPH M. VAIL, OF BRYAN, OHIO.

RAIL-STAY.

1,131,751.

Specification of Letters Patent. Patented Mar. 16, 1915.

Application filed August 24, 1914. Serial No. 858,281.

To all whom it may concern:

Be it known that I, JOSEPH M. VAIL, a citizen of the United States, and a resident of Bryan, in the county of Williams and State of Ohio, have invented a certain new and useful Rail-Stay; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to stays for railway rails for preventing a relative creeping of the rails and supporting ties in one direction.

The object of my invention is the provision of an improved device of this character, and has particular reference to improvements on the rail stays covered by my prior Letters Patent No. 1,091,603, dated March 31, 1914.

The invention is fully described in the following specification, and while, in its broader aspect, it is capable of embodiment in numerous forms, two preferred embodiments thereof are illustrated in the accompanying drawings, in which,—

Figure 1 is a perspective view of a device embodying the invention separate from a rail. Fig. 2 is a top plan view of portions of a rail and tie with the device operatively connected therewith, and Figs. 3 and 4 are similar views, respectively, of a slightly modified form of the device.

Referring to the drawings, 1 designates a railway tie, and 2 a rail supported thereby. The device embodying the invention comprises two separably connected members, one of which, for convenience, may be termed the cross-bar or body member, and the other the thrust member, the former extending under the rail substantially diagonally thereof, and the latter having engagement with the former and having a part in contact with a side of a tie and cooperating with the body member to grip the rail base. The cross-bar or body member of the device, in the present instance, comprises a bar 3 which is intended to extend in a diagonal manner under a rail base, and has one end provided with a head 4 having a slot or recess 5 in the inner side thereof for receiving the adjacent edge of a rail

base, the recess 5 preferably being vertically spaced from the upper surface of the bar 3 to provide a space between the under side of an engaged rail and the top of the bar. 60 The bar 3 is preferably of sufficient length for the end thereof opposed to the head 4 to extend substantially to the opposite edge of the rail base when applied thereto.

The thrust member of the device comprises, in the present instance, a block or head 6 for extending lengthwise of a rail and having its outer end preferably enlarged to adapt it to abut against a side of a tie 1, and its inner side edge longitudinally recessed, as at 7, to receive the adjacent edge portions of a rail base. The end of the thrust member 6, which is opposed to the tie abutting end thereof, is preferably adapted to project over the free or adjacent end 70 portion of the cross-bar 3 and has releasable engagement with the cross-bar for sliding movements relative thereto longitudinally of the engaged rail.

In Figs. 1 and 2 I have shown a dove-tail 80 tongue and groove connection between the bar 3 and thrust member 6 to retain the same in releasable assembled relation and to permit a relative movement thereof longitudinally of a rail base. In this form, 8 designates a tongue or rib of dove-tail form 85 in cross-section, which is provided on the upper surface of the bar 3 adjacent to its free end and extends in a direction substantially parallel with the longitudinal 90 axis of the rail when the bar 3 is in its proper diagonal position relative to the rail. The end of the thrust member 6 opposed to the tie abutting end thereof is provided on its under side with a longitudinally extending 95 complementary groove or recess 9 for receiving the tongue 8 for longitudinal sliding engagement therein, said groove being open at the free or rear end of the thrust member and provided with a thrust wall at its 100 opposite end against which the adjacent end of the tongue 8 is adapted to abut when inserted to its maximum extent into the groove. It is thus evident that the tongue and groove are moved into engagement 105 from the tie side of the bar 3, and that when the tongue and the closed end of the groove are in abutment an end thrust on the member 6, such as would be exerted by a tie upon a movement of an engaged rail in one direction over the tie, would cause a thrust to be exerted on the tongue 8, or, in other words,

the tongue 8 would oppose the tie actuated thrust of the member 6. It is thus evident that the tongue and groove connection between the members 3 and 6 tends to retain 5 the opposed rail base engaging portions of said members in clamping engagement with a rail base, and also provides a thrust connection between said members for communicating a tie actuated longitudinal movement 10 of the member 6 to the connected end of the member 3 as is apparent.

In Figs. 3 and 4 the connecting means between the members 3 and 6 takes the form of a pivotal stud and slot connection. The 15 stud 10, in the present instance, projects upward from the upper surface of the bar 3 adjacent to its free end and engages a slot or opening 11 in the member 6, such slot or opening being elongated longitudinally of 20 the member 6 to allow for a limited longitudinal movement of the thrust member relative to the stud 10.

A spring-arm 12, which is preferably, but not necessarily, of looped form, as shown, 25 projects transversely from the forward end of the thrust member 6, or the end thereof connected to the bar 3, between the bar 3 and rail base and has its free end sprung into catch engagement with the end surface 30 of the bar head 4 when the parts are in assembled engagement with a rail. When the free end portion of the bar 3 and thrust member 6 are connected, the free end of the spring-arm 12 normally stands at the inner 35 side of the head 4 of the bar so that it is necessary to exert pressure thereon to swing the free end of the arm away from the associated tie and in thrust engagement with the head surface 13. It is thus evident that 40 the spring connection which I have provided between the thrust member 6 and the headed end of the bar 3 yieldingly resists a movement of the thrust member toward the engaged tie relative to the bar 3.

45 The connecting of the members 3 and 6 in a manner to permit a sliding movement of the thrust member relative to the bar 3 longitudinally of a rail and the yieldingly retaining of said members in assembled relation 50 with their interengaged parts in thrust contact, whereby a tie actuated movement of the thrust member 6 communicates a corresponding movement to the bar 3, are found to be very important features in a rail stay.

55 When the rail stay is in use it, or at least the flange tie abutting end of the thrust block 6 thereof projects down into the road ballast so that when a freezing occurs after a thaw or rain such block 6 will be securely 60 anchored in the ballast. In practice it is very frequently found that the change in temperature at such times causes a jumping back or a movement of the rail in a direction opposed to its direction of creeping and 65 that the rail in its backward movement car-

ries with it a portion of the members of a rail stay having relatively movable parts, the other portion of the members being held anchored in the ballast. With most rail stays the separation of the members in this manner permits a permanent disconnection thereof so that they will no longer be of service in preventing a creeping of the rail without replacing them on the rail. With my invention the bar 3 is drawn rearwardly 70 by the rail in its creeping action while the thrust block 6 remains stationary, such relative movement of the members being permitted by reason of the tongue and groove connection in one form and the pin and slot connection in the other form of the members. Upon a releasing of the thrust-block 6 from the ballast when a thaw occurs, the spring arm 12 will cause a return movement 75 of the thrust-block 6 to its normal position relative to the bar 3 and prevents a falling apart of the members.

I wish it understood that my invention is not limited to any specific construction, arrangement or form of the parts except in so far as such limitations are specified in the 80 claims.

Having thus described my invention, what I claim as new, and desire to secure by Letters Patent, is,—

1. A rail stay of the class described comprising two members having opposed engagement with opposite sides of a rail base and one intended to have thrust contact with a tie, said members having limited sliding interengaging connection, and means for yieldingly resisting a relative movement of said members lengthwise of the rail and operable to automatically return the members to normal rail base gripping position 100 when a force acting to relatively move the members is removed.

2. A rail stay having a pair of opposed rail base clamping members interengaged for relative sliding movements lengthwise 110 of a rail, and means connecting the two members and operable to yieldingly retain the members in rail base clamping position, to resist a rail base releasing movement of the members and to return the members to 115 normal rail base clamping position when a force tending to impart relative rail base releasing movement to the members is removed.

3. A rail base having a pair of opposed rail base gripping members, one extending under and the other lengthwise of an engaged rail, said members having parts interengaging for limited relative sliding movements lengthwise of a rail and having parts 125 in yielding connection and tending to retain said first mentioned parts in interengaged thrust contact whereby a thrust of one member in one direction will be exerted on the other.

4. A rail stay having a pair of opposed rail base clamping members in sliding inter-engagement beneath a rail for relative sliding movement lengthwise of an engaged rail, 5 said members having parts in yielding co-action for yieldingly resisting a relative movement of the interengaged portions of said members in one direction and for returning them to normal position after being 10 relatively moved.

5. A rail stay having a bar extending under a rail and having a rail-base edge-engaging part at one end, a tie thrust member for engagement with the opposite base edge 15 of a rail, said bar and member having portions releasably interengaged for relative sliding movements longitudinally of a rail and adapted to coact to exert a thrust from one part to the other, said bar and member 20 having parts in yielding engagement and co-operating to normally retain said interengaged parts in engaged thrust contact.

6. A rail stay having a pair of opposed rail-base gripping members provided beneath the rail with interengaged parts which connect the members for relative sliding movements longitudinally of an engaged rail and adapted to have thrust coaction to tend to exert a movement from one member 25

to the other lengthwise of the rail, said member also having parts which are yieldingly connected and operate to yieldingly retain said engaged parts in thrust contact and to return them to normal position after being relatively moved in one direction. 30

7. In a rail stay, a body member and a thrust member each having opposed rail base gripping parts, said body member extending under a rail from its gripping part and having releasable sliding engagement 35 with the thrust member adjacent to its rail base gripping portion whereby the members are permitted to have limited relative sliding movements lengthwise of a rail in one direction, and a spring-arm projecting from 40 said thrust member under a rail and coacting with a part of said body member to yieldingly retain the engaged portions of 45 the members in predetermined positions of their relative movements. 50

In testimony whereof, I have hereunto signed my name to this specification in the presence of two subscribing witnesses.

JOSEPH M. VAIL.
